UNITED STATES PATENT OFFICE.

HERMANN RIEMANN, OF CHEMNITZ-GABELNZ, GERMANY.

ACETYLENE-GAS LAMP.

SPECIFICATION forming part of Letters Patent No. 639,434, dated December 19, 1899.

Application filed March 23, 1899. Serial No. 710,247. (No model.)

To all whom it may concern:

Be it known that I, HERMANN RIEMANN, manufacturer, a subject of the King of Saxony, residing at Chemnitz-Gabelnz, in the 5 Kingdom of Saxony, and German Empire, have invented certain new and useful Improvements in Acetylene Lamps or Generators, of which the following is a specification.

My invention relates to acetylene lamps or 10 generators, and provides an efficient means of securing the carbid-holder to the lamp or generator in an air-tight and secure manner.

In the accompanying drawings, Figure 1 is 15 a vertical section, and Fig. 2 a horizontal section, on the line X Y of Fig. 1, of the invention as provided for the carbid-holder of an acetylene-lamp.

The arrangement is as follows: The carbid-holder A is contained in a case B, the upper 20 rim or part of which is provided with two or more hooked flanges or plates C. The lower part of the body or base of the lamp or generator D is formed into or provided with a circular flange E, broken away at parts, so as 25 to form free spaces F of a width equal to or greater than that of the hooked flanges C and to correspond as regards position with said hooked parts. The circular flange E is shaped like a gutter, open at its upper end, so that 30 when the two parts are placed together the hooked parts pass through the free space, and then by rotating the two parts relatively to each other the hooked parts will engage in the corresponding channels in the lamp-body 35 flange, thereby forming a bayonet-joint. To render this joint air-tight and to provide against any accidental disengagement, the bottom B of the case B is provided with a screw S, (or it may be a strong spring,) the end of 40 which is applied to the bottom A of the carbid-holder A, which screw S can be turned from the outside in order to press the carbid-holder A against the body D of the lamp, which is provided with suitable packing, and 45 to draw the case B downward with such force that a firm and unyielding interlocking of the bayonet-joint is secured. In such manner a perfectly gas-tight connection is secured by a device which may be readily locked 50 or unlocked when required.

Of course the interlocking device may be arranged on the inside instead of on the outside of the part to be connected.

Instead of the case B a simple yoke (or yokes) with its ends bent inward may be used; but 55 the first-described arrangement will be found to possess great merits over the other modifications, inasmuch as a securing device is obtained which in consequence of its smooth and neat appearance and its absence of projections, levers, and screws will always commend itself.

Having now particularly described and ascertained the nature of my said invention and in what manner the same is to be performed, 65 I declare that what I claim is—

In an acetylene-gas lamp, the combination with the lamp-body having an annular depending rim upon opposite sides thereof provided with circumferentially-arranged integral flanges E, separated from each other by spaces F, said flanges extending partially around the lamp-body and having their edges bent outward and upward to provide prolonged hooked portions, an annular packing-ring G, seated in the upper part of the lamp-body and inclosed by said rim, of a removable carbid-holder adapted to make contact at its upper edge against the packing-ring, a case B, inclosing the carbid-holder and having inwardly and downwardly bent hooked portions C, upon opposite sides thereof at the top arranged to enter the said spaces F, between the flanges E, and fit over the latter when the case is turned away from the said spaces F, 70 and a screw tapped through the bottom of the case and arranged to act upon the under side of the carbid-holder to force the upper edge thereof against the packing-ring to effect a tight closure of these parts, substantially as described.

In testimony whereof I have hereunto set my hand in presence of two subscribing witnesses.

HERMANN RIEMANN.

Witnesses:
